UNITED STATES PATENT OFFICE

GERMÁN ALBERTO AÑEZ AÑEZ, OF MARACAIBO, VENEZUELA

LOCK

Application filed November 9, 1928. Serial No. 318,189.

This invention relates to improvements in locks and has for its object to provide a lock which is capable of a multiplicity of uses as, for instance, an ordinary padlock, a door lock and a trunk lock.

A further object is the provision of a lock wherein the various locking members may be rendered inoperative when other of the locking members are to be employed, thus permitting either the separate or simultaneous use of the several locking members.

A still further object is the provision of a lock wherein the locking is effected by the combined action of permutation means and a key controlled releasing element.

In the accompanying drawings wherein a preferred embodiment of the invention is illustrated—

Fig. 1 is a front elevation of the improved lock adapted for use as a padlock.

Fig. 2 is a similar view with the cover plate turned back.

Fig. 3 is a view similar to Fig. 2, the cover plate being omitted and the shackle shown in open position.

Fig. 4 is a detail view of the lock showing the padlock shackle removed and replaced by a keeper such as ordinarily used in trunk locks. In this view the casing is inverted relatively to the position shown in Fig. 1.

Fig. 5 is an elevation of the lock with the padlock shackle removed and showing the bolt projected.

Fig. 6 is a detail view of the interior of the casing with the internal parts removed.

Fig. 7 is an elevation of the key.

Fig. 8 is a detail view of the locking element removed.

Fig. 9 is a detail elevation of the key on an enlarged scale.

Fig. 10 is a detail view of the wire locking member associated with the bolt adapted to coact therewith to retain the latter in retracted position.

Fig. 11 is a detail section on the line 11—11 of Fig. 3.

The lock is constituted by a casing 10 of box-like form including the rear wall 11 and the four side walls 12, 13, 14 and 15, the front of the casing being open. The open

front of the casing is normally closed by a cover plate 16 which, aside from being secured in place by conventional securing means, such as screws, or the like, is further locked in place by certain of the internal moving parts of the lock in a manner which will be hereinafter more fully described.

The lock includes a pivoted padlock shackle 17, a door lock bolt 18 and a trunk lock bolt 19 all three of which are controlled by a single locking element 20. The actuating element is moved to inoperative position by a rotary releasing member and maintained in locked or operative position by key controlled permutation means as will be hereinafter more fully described. The several bolts and the shackle, although capable of simultaneous operation and control, are also capable of independent use, and in that case certain of them may be held in inoperative position.

The shackle 17 consists, as usual, of the curved member 17 having a recessed end 21, the opposite end being pivotally mounted in the case by a pin 22 to permit swinging movement of the shackle. An angular bolt 23 adapted to enter the recess in the end 21 of the shackle to lock the latter in closed position is mounted in the case 10 and guided by an angular rib 24 therein and normally projected to shackle locking position by an expansion spring 25.

One extremity of the bolt 23 is located in the path of the upper extremity of the releasing element 20 so that when the latter is retracted or moved to inoperative position the bolt 23 is free to be displaced and engaged in the notch 21 of the shackle 17.

To permit of the removal of the shackle 17 from the lock casing 10 when so desired, the pin 22 may be removed, thus releasing and permitting withdrawal of the pivoted extremity of the shackle.

The side wall of the casing 10 opposite the shackle 17 is provided with slots 26a shown in the lower portion of Fig. 3 for accommodating the loops 26 of the trunk lock keeper 27 which, when inserted in said slots, are engaged by the bolts 19 of the locking element 20.

The intermediate portion of the locking

- element 20 is adapted to cooperate with the door locking bolt 18 and is connected therewith at will by a pin 28 passing through the aperture 29 in the element 20 and a registering aperture 30 in the bolt 18 whereby movement of the element 20 is transmitted to the bolt 18. Said bolt is provided with a second aperture 31 which, in the retracted position of the bolt, registers with a recess in the wall 11 of the casing and upon insertion of the pin 28 locks said bolt in inoperative position and, said pin having been removed from the element 20, permits free movement of the latter independently of the bolt 18.
- 15 The locking element 20 is normally moved to operative position by springs 32 and 33 confined between it and the side wall 15 of the casing and it is suitably guided in the latter by guide members 34.
- 20 The cover 16 is partially retained in position by lugs 35 entering recesses in the side wall 15 and is provided with a lug 36 having an aperture therein adapted to receive the pin projection 37 of the element 20 whereby
- 25 when the latter is in operative or locking position the cover 16 is locked in place.
- Three or more tumbler discs 38 are rotatively mounted on a pin 40 in the casing 10 and each is provided with a recess 41a. When
- 30 the recesses of all of the discs are moved into registration and properly positioned they are adapted to accommodate the lug 41 of the locking element 20 whereby the latter may be retracted to release the shackle 17 and the bolts 18 and 19.
- 35 Movement of the front-most disc 38 is transmitted to the other discs by the usual inter-engaging lugs 43, said lugs act, as usual, to transmit movement from one disc to the other. The front-most disc 38 is provided with two recesses 43 which are exposed
- 40 through a key hole 44a in the cover 16.
- A rotatable releasing member 44 is pivoted at 45 in the casing 10 at the side of the element 20 opposite the discs 38 and upon
- 45 being turned to the proper position, it places the element 20 against the tension of the springs 32 and 33, provided the discs 38 are in proper position, thus permitting the opening of the shackle 17 effecting the retraction
- 50 of the bolts 18 and 19. The rotatable releasing member 44 is provided with recesses 46.
- A key 47 having a bifocated extremity 48 is adapted for insertion in the recesses 43 whereby the discs 38 may be properly set, and
- 55 subsequent to this operation the key is removed from the key hole 44a, inserted in the recesses 46 through the key hole 49 and upon being turned effects the movement of the locking element 20 to inoperative position. The
- 60 key 48 is provided with a graduated scale 50 which is movable relatively to a mark 50a on the casing to aid in setting the discs 38. The end of a steel wire 51 is adapted to be inserted in a recess 56 provided in the casing and to
- 65 lie within a transverse recess 55 formed in

the bolt 18 whereby to retain the latter in retracted position when the bolt is not in use. When removed, the wire may be inserted beneath the spring 32 in which position it is held, as shown in Fig. 3 in dotted lines.

As will be understood from the foregoing the shackle 17 and bolts 18 and 19 may all be used simultaneously, if so desired, and being distributed over three of the four side walls of the casing, are capable of convenient use. On the other hand, the shackle 17 may be dispensed with, if desired, by removal of the pin 22, or the bolt 18 may be locked against operation by insertion of the pin 28 in the opening 31 and recess of the wall 11. The bolts 19 are at all times operated by the element 20, but when the latter is in locked position they close the slots in the side wall 14 and prevent tampering with the internal parts of the lock. The bolt 18 is provided with a groove 55 which in its retracted position receives the wedge portion of the U-shaped steel wire 51, one angular terminal of which is longer than the other and is adapted to engage in an aperture 56 in the wall of the casing to retain the bolt in retracted position.

The graduated scale 50 of the key is formed in two parts embracing the shank of the key and when said parts are folded lie flatly upon said key shank. The latter is provided with a series of recesses 57 and when the parts of the scale 50 are extended into right angular position they enter the one or the other of the recesses 57 and retain the scale 50 in adjusted position, thus adapting the key to use according to various types of mountings of the lock.

What I claim is:

In a lock, a casing, a locking element movable therein, tumbler discs adapted to coact with the locking element to maintain the latter in locking position, spring means normally tending to move the locking element to locking position, a rotatable key controlled member adapted to retract the locking element, a bolt slidably mounted in the casing, and a pin passing through the locking element and bolt to cause movement of the latter with the locking element, said pin being removable whereby the bolt may be uncoupled from the locking element, a clip member adapted to embrace the bolt and engage the casing to retain the bolt in retracted position when the pin is removed from the locking element.

In testimony whereof I affix my signature.
GERMÁN ALBERTO AÑEZ AÑEZ.
